His Attorney

UNITED STATES PATENT OFFICE

GEORGE HEGEMAN HART, OF WEST HARTFORD, CONNECTICUT.

AUTOMATICALLY CONTROLLED SWITCH.

Application filed November 20, 1924. Serial No. 751,049.

This invention relates generally to electric switches, for example, switches which are automatically controlled, for instance thermostatically, and have covers by means of which the switches may be set or adjusted, end of this screw protrudes into the opening in which the covers are connected to the base or supporting body.

An object of the invention is to provide improved means having various features of novelty and advantage for holding the cap or cover of the switch in place and for rotary adjustment.

A more specific aim of the invention is to provide an improved arrangement by means of which the cover may be very quickly and readily assembled on the base and removed therefrom.

A further object is to provide means for holding the cover in place which is very simple and economical in construction and efficient in operation.

A still further aim is to provide means for holding the cap or cover in place without the use of screws or similar securing means; the securing means in the present disclosure being entirely concealed from view by the cover.

Another object is to provide a construction which will permit the cover to be readily removed and replaced without impairing the setting or adjustment of the switch which it houses.

Other objects will be in part obvious and in part pointed out more in detail herein-after.

The invention, accordingly, consists in the features of construction, combination of elements and arrangement of parts which will be exemplified in the construction herein-after set forth, and the scope of the application of which will be indicated in the appended claims.

In the accompanying drawings, wherein I have shown, for illustrative purposes, one embodiment which the present invention may take:

Figure 1 is a view of a thermostatically controlled electric switch with the cover or cap thereof in section;

Fig. 2 is a horizontal sectional view taken substantially on line 2—2 of Fig. 1, with the cover turned counterclockwise through an angle of substantially 90 degrees;

Fig. 3 is a sectional view taken substantially on line 3—3 of Fig. 2, but with the

cover raised slightly from the position which it occupies in Fig. 2;

Fig. 4 is a detail view of that side of the base of the switch diametrically opposite to that observed in Fig. 1; and

Fig. 5 is a plan view of what is illustrated in Fig. 4, and shows, additionally, the relation of the cover to the base when the cover is in position to be removed.

In Fig. 1 of the accompanying drawings, I have shown the features of the present invention applied to a thermostatically controlled switch similar to that disclosed in the application for U. S. Letters Patent of Gerald W. Hart, Serial No. 675,092, filed November 16, 1923, but it is to be understood that the present disclosure is by way of illustration only and that my invention is not limited in use to the specific embodiment here illustrated.

Referring to the drawings in detail, the electric switch proper includes a pair of contacts 10 and 11, and a switch arm 12 having, in its free end, an insulated circuit closing member or pin 13 positioned between the contacts 10 and 11. The other end of the switch arm is pivoted in a lug or bracket 14. The terminals 10 and 11 and the bracket 14 are mounted on a plate 15 of insulating material located within a base 16 of suitable construction. The circuit closing member 13 is normally urged towards the terminal 10 by a leaf spring 18 which also serves as a conducting member, as explained more in detail in the said Gerald W. Hart application. The respective terminals 10 and 11 are adapted to be connected to lead wires (not shown).

The switch is automatically operated by a suitable responsive device, such, for instance, as a thermostat, which may include a tube 20 having a relatively high co-efficient of expansion and a rod 21 within the tube and having a relatively low co-efficient of expansion. The tube may be connected to the base 16. The switch is associated with the thermostatic device by means of a plunger 22 having a head 23 normally urged against the upper end of the rod 21 by a spring 24. The plunger extends upwardly through the plate of insulating material 15 and a bracket 26. Cooperating with the switch arm 12 is a lever 28 pivoted as at 29 and extending through a transverse opening 30 in the upper end of the plunger. For the purpose of varying the effective length of the plunger,

- and thereby adjusting the device to operate at any predetermined temperature, there is provided in the upper end of the plunger an adjustable member which is shown as being in the form of a screw 31. The lower end of this screw protrudes into the opening 30 and engages the upper edge of the lever 28. The screw is preliminarily adjusted within the plunger to determine the range of temperature within which the thermostatic device will actuate the switch. In order to set or regulate this screw so that the thermostatic device will actuate the switch at any desired predetermined temperature within the selected range, the screw is connected to a rotatable cover 32 which carries one element of the temperature indicating means. This element, in the present instance, takes the form of a scale cooperating with an indicating mark or pointer 33 on the base. The scale may be provided on a sheet of metal 34 which closely surrounds the cylindrical portion of the cover and is suitably secured thereto. The cover may be adjustably connected in any suitable manner to the screw 31 as, for example, by means of a lug 35 engaging in the kerf of said screw. The arrangement so far described is similar to that illustrated in said Gerald W. Hart application.
- Referring now to the improvements of the present invention, the base 16 has a cylindrical portion about which the lower or open end of the cover fits, and this cylindrical portion has a circumferential groove 38 in which is adapted to engage one or more projections or lugs on the cover. In the present instance, two such lugs 39 and 40, diametrically positioned, are provided. These lugs may be formed in any suitable manner but, for the sake of simplicity, and to effect economy in manufacture, they are made by indenting the wall of the cover. By grooving the cylindrical portion of the base, as at 38, there is provided a circumferential rib 41, against the under face of which the lugs 39 and 40 engage when the cover is in position. The edge of the cover abuts against the shoulder or flange 42. To permit the cover to be assembled onto, and dissembled from, the base, the rib 41 is notched at diametrically opposite points, as at 43 and 44. These notches may be considered as constituting grooves leading into the circumferential groove 38.
- For the purpose of preventing the cover from being accidentally or inadvertently removed from the base, one of the notches, in the present instance the notch 43, is normally obstructed or interrupted by a stop 46 which is preferably in the form of a plunger pressed outwardly by a spring 47. The projecting end of the stop is rounded or crowned, as shown, and, preferably, the lug 39, which is adapted to cooperate with this stop, is also domed or rounded so that, when sufficient force is applied, the lug 39 will cam the plunger back, whereupon the lug may be moved through the notch or groove 43. In order that the lugs 39 and 40 may be respectively brought into registry with the grooves or notches 43 and 44, when it is desired to remove the cover, there is provided, within the groove 38, a stop 48 having a shoulder 49 in alignment with one edge of the notch 44, as shown most clearly in Figs. 4 and 5.
- The operation of the device is briefly as follows: When it is desired to remove the cover from the base, the former is turned, in the present instance, counterclockwise, whereupon the lug 39 is brought into engagement with the retractile stop or plunger 46, with the result that the latter is cammed inwardly to the position shown in Fig. 2, thus permitting the lugs 39 and 40 to be brought into registry with the grooves 43 and 44, respectively. The stop 48 serves to limit rotary movement of the cover or cap to the position shown in Fig. 2. The cover may now be slipped from place. When it is desired to assemble the cover onto the base, it is merely necessary to bring the lugs into registry with the notches and then force the cover downwardly, whereupon the lug 39 cams the plunger 46 inwardly, and then the cover may be rotated to engage the lugs beneath the rib 41 and to set or regulate the screw 31 so that the thermostatic device will actuate the switch at any desired temperature within the selected range.
- From the foregoing description, it will be seen that the means for securing the cover to the base is very simple and economical in construction. The use of screws or the like is eliminated, and the securing or holding means is entirely concealed. The cover cannot become accidentally removed from the base, while, at the same time, it may be deliberately removed and replaced very readily and quickly. The cover may be removed and replaced without disturbing the adjusted relation of the screw 31 to the plunger.
- As many changes could be made in the above construction and many apparently widely different embodiments of this invention could be made without departing from the scope thereof, it is intended that all matter contained in the above description or shown in the accompanying drawing shall be interpreted as illustrative and not in a limiting sense; for instance, the retractile stop may have a form other than a spring pressed plunger and, instead of being cammed out of the way by the cover, it may be retracted by a separate instrument.
- It is also to be understood that the language used in the following claims is intended to cover all of the generic and spe-

cific features of the invention herein described and all statements of the scope of the invention which, as a matter of language, might be said to fall therebetween.

5. I claim as my invention:

1. In a device of the character described, a body having a cylindrical portion provided with a circumferential groove and a notch entering thereinto, a rotary cover having a skirt portion encircling said cylindrical portion and provided with a lug adapted to enter said notch and engage in said groove, and resilient means in said groove and against which said lug is adapted to engage for preventing accidental removal of the cover from said body, said lug being movable in said groove to permit angular adjustment of said cover, and said resilient means engaging said cover and acting as a drag thereon to hold the cover in any desired position of adjustment.

2. In a device of the character described, a body having a cylindrical portion provided with a circumferential groove and a notch entering thereinto, a rotary cover having a skirt portion encircling said cylindrical portion and provided with a lug adapted to enter said notch and engage in said groove, and a spring pressed member projecting into said groove at said notch for preventing said lug from freely registering with said notch, said lug being movable in said groove to permit angular adjustment of said cover, and said resilient means engaging said cover and acting as a drag thereon to hold the cover in any desired position of adjustment.

3. In a device of the character described, a body having a cylindrical portion provided with a circumferential groove and a notch entering thereinto, a rotary cover having a skirt portion encircling said cylindrical portion and provided with a lug adapted to enter said notch and engage in said groove, and resilient means in said groove and against which said lug is adapted to engage for preventing accidental removal of the cover from said body, said lug and resilient means having co-acting cam surfaces whereby said lug may cam said means out of the path of the lug.

4. In a device of the character described, a body having a cylindrical portion provided with a circumferential groove and a notch entering thereinto, a rotary cover having a skirt portion encircling said cylindrical portion and provided with a lug adapted to enter said notch and engage in said groove, and a spring pressed member projecting into said groove at said notch for preventing said lug from freely registering with said notch, said lug and member having rounded surfaces adapted to engage, whereby said lug may cam said member out

of the way when it is desired to remove the cover from the body.

5. In a device of the character described, a body having a cylindrical portion provided with a rib, a rotary cover having a skirt portion encircling said cylindrical portion and provided with a lug adapted to engage behind said rib, said rib having a notch through which said lug may pass, and a spring pressed plunger carried by said body portion and normally obstructing said notch said lug being formed by indenting the metal of said cover and having a rounded surface adapted to engage said plunger to retract the same when it is desired to assemble the cover on, and disassemble the same from, said body.

6. In a device of the character described, a body having a cylindrical portion provided with a circumferential groove and a notch entering thereinto, a rotary cover having a skirt portion encircling said cylindrical portion and provided with a lug adapted to enter said notch and engage in said groove, a spring pressed member projecting into said groove at said notch for preventing said lug from freely registering with said notch, and means for limiting the rotary movement of said cover relative to said body to a position where said lug registers with said notch.

7. In a device of the character described, a body having a cylindrical portion, a rotary cover having a skirt portion encircling said cylindrical portion, one of said portions being provided with a rib and the other of said portions having a pair of lugs adapted to engage behind said rib, said rib having a pair of notches through which the respective lugs may pass when assembling the cover on, and disassembling it from, said body means associated with one of said notches for preventing the lugs from freely registering therewith, and means for limiting rotary movement of said cover relative to said body to a position where said lugs register with said notches.

8. In a device of the character described, a body having a cylindrical portion provided with a circumferential groove and a pair of notches entering thereinto, a rotary cover having a skirt portion encircling said cylindrical portion and provided with a pair of lugs adapted to enter the respective notches and engage in said groove, a spring pressed member projecting into said groove at one of said notches for preventing said lugs from freely registering with said notches, and means associated with the other of said notches for limiting rotary movement of said cover relative to said body to a position where said lugs register with said notches.

9. In a device of the character described, a body having a cylindrical portion provided with a circumferential groove and a pair of notches entering thereinto, a rotary cover

having a skirt portion encircling said cylindrical portion and provided with a pair of lugs adapted to enter the respective notches and engage in said groove, a spring pressed 5 plunger projecting into said groove adjacent one of said notches for preventing said lugs from freely registering with said notches, said member and the lug adapted to operate therewith having rounded surfaces 10 whereby said lug may cam said member out of the way, and a shoulder in said groove adjacent said other notch and against which the other of said lugs is adapted to engage.

10. In a device of the character described,

and in combination, a base having a cylindrical portion, an automatically operated switch within said base, a cover associated with said switch for regulating the same, said cover having a skirt portion encircling said cylindrical portion of said base, said 20 cylindrical portion having a circumferential groove and a notch entering thereinto, said skirt portion having a lug adapted to enter said notch and engage in said groove, and spring pressed means projecting into said 25 groove for preventing said lug from registering with said notch.

GEORGE HEGEMAN HART.
